UNITED STATES PATENT OFFICE.

JOSEPH WALMER AND CHARLES EMERY, OF LUDLOW, KENTUCKY; SAID
EMERY ASSIGNOR TO SAID WALMER.

SPRING BED-BOTTOM.

SPECIFICATION forming part of Letters Patent No. 238,540, dated March 8, 1881.

Application filed December 8, 1879.

To all whom it may concern:

Be it known that we, JOSEPH WALMER and CHARLES EMERY, of Ludlow, in the county of Kenton and State of Kentucky, have invented 5
an Improved Sectional Spring Bed-Bottom, of which the following is a specification.

Our invention relates to bed-bottoms which are made in sections, so as to be easily removed and replaced.

10 In our device twin springs and paired slats are used, the slats for supporting the springs and the springs for securing two slats together and supporting the bed. The paired slats are constructed with excavations or recesses on 15 the opposing sides for the reception or insertion of the upturned ends of the springs, which are of twin form. These recesses are for the purpose of retaining the springs in their proper position and preventing them from slipping 20 sidewise. Each twin spring is constructed of one continuous wire, the coils being connected at top by a V-bend, bringing them close together, and formed at bottom with certain bends, providing secure holds for receiving the 25 slats sidewise.

In order that our invention may be fully understood, we will proceed to describe it with reference to the accompanying drawings, in which—

30 Figure 1 is a top view of twin springs of our improved construction applied to a pair of slats. Fig. 2 is a side view, the slats being sectioned transversely to show the locked ends of the springs. Fig. 3 represents our improved 35 paired slat and twin-spring bed-bottom.

A A' represent a pair of slats provided with excavations or recesses a a' adapted to receive the upturned ends b'' b''' of twin springs B B'. The lower portions of the springs rest on the 40 slats, and are bent horizontally away from each other, as at b b, thence down the outer

edge of the slats, as at b' b', thence horizontally inward under the slats, as at b'' b'', terminating in the short upturned ends b''' b''', which form catches. 45

The advantages gained by our construction will be apparent, but a few will be referred to.

First, the section consisting of a pair of slats and accompanying springs can be lifted out without the possibility of the slats falling out 50 sidewise.

Second, the slats being secured by the upturned ends b''', they can be easily removed by depressing them from above.

Third, the springs can be secured at proper 55 intervals apart.

Fourth, by securing their ends in recesses the springs are locked from sidewise movement on the slats.

We are aware that we are not the first to 60 construct a bed-bottom of twin springs and slats, and we do not therefore claim such as our invention.

Our invention consists in the mode of constructing and applying such springs to the 65 slats.

Having thus described our invention, the following is what we claim as new therein and desire to secure by Letters Patent:

The combination of the slats A A', having 70 notches or recesses a a' in the vertical sides thereof, and the twin springs B B', formed with short upturned ends b'' b''', adapted to be readily slipped in and out of the said recesses, as and for the purpose set forth. 75

In testimony of which invention we hereunto set out hand.

JOSEPH WALMER.
CHARLES EMERY.
